UNITED STATES PATENT OFFICE.

MARK S. HOTCHKISS, OF JOHNSON CITY, NEW YORK.

ROAD RAIL OR FORM.

Application filed March 2, 1925. Serial No. 12,604.

To all whom it may concern:

Be it known that I, MARK S. HOTCHKISS, of 51 Grand Avenue, Johnson City, in the county of Broome, in the State of New York, have invented new and useful Improvements in Road Rails or Forms, of which the following is a description, reference being had to the accompanying drawing, forming a part of this application.

This invention relates to road rails or forms of the type commonly used for defining the contour and grade of the marginal edges of concrete, asphalt, or other forms of pavements, roadways, or walks during the process of construction.

These road rails are necessarily made in sections preferably of sheet steel rolled or pressed to the desired form and arranged end to end along the edges of the proposed pavement for imparting the desired regularity of finish and also for establishing the desired grade of the upper surfaces of said edges, while the pavement is under construction, it being understood that the upper surface of the adjacent portions of the pavement are finished substantially flush with the top faces of the road-rails along and upon which the surfacing machines are adapted to ride, and the main object of my present invention is to provide a light, strong and durable road-rail which may be easily and quickly installed in proper alinement along the edges of the road-bed and which will maintain its longitudinal and vertical alinement under the various strains to which it may be subjected during the construction and finishing of the pavement.

More particularly, it is the object of this invention to provide a novel and practical staking device and securing means therefor, which can be depended upon for rigidly holding the rail sections in their alined positions, and which may be readily assembled or quickly removed.

Another object contemplates a new and improved type of wedge or cam locking member for engagement with the stake, insuring a secure clamping action therewith.

A still further object lies in the provision of reinforcing means for the cam or wedge locking surface.

Other objects and advantages in details of construction and operation will be apparent as the description proceeds, reference being had to the accompanying draw-

ing wherein like reference characters indicate like parts.

My invention is an improvement upon that patented in Letters Patent No. 1,492, 60 325—April 29, 1924.

In the drawing:

Figure 1 is a perspective view of a portion of one of my improved road rails, illustrating in operative position my new stake 65 locking or securing device.

Figure 2 is a cross section of my stake locking device, taken on the line 2—2 of Figure 1.

Figure 3 is another section, taken on line 70 3—3 of Figure 1.

I have illustrated at 1 a section of a partially completed pavement, the contour and grade of which is defined and the body of which is supported laterally by my improved form or rail, part of one section of which is shown in Figure 1. It will be understood by those skilled in the art that the rail form for a given length of roadway is made of sections, resting end to end and 75 removably secured together in any suitable manner which permits ready assembly and dismantling thereof.

For clearness of description, part of one rail section only has been shown, and includes a base flange 2 extending outwardly and laterally of the edge of the pavement. This base flange rests on the ground and supports the vertical side 3 against which abuts the edge of the pavement. The height 80 85 of this flat vertical side 3 is preferably exactly that of the pavement to be built, the materials thereof being filled in to a point flush with the top of said side 3.

Formed outwardly and at right angles to the side 3 is an upper flange 4, extending parallel with the base flange 2, but preferably of lesser width than said base flange. Extending downwardly from the outer edge of the top flange 4 is a short flange 5 parallel with the side wall 3 and defining at the upper edge of the rail or form, a channel 6.

Means are provided for securing the rail or form in rigid supporting position on the ground, including a substantially U 105 shaped bracket having its closed sides 7 and 8 positioned one above the other respectively. The upper arm 7 of this bracket is formed upwardly at right angles thereto, extending as at 7^a into the channel 6 where 110 it is again bent at right angles, as at 9, such right angled portion lying parallel

with and adjacent to the underside of the top flange 4 of the rail.

The inner end of the lower side 8 of the bracket is formed downwardly at right angles thereto, as at 10, and in alignment with the arm 7^a. Secured to the base flange 2 of the rail, as by rivets 11, is the lower right angled support of an upwardly extending guide plate 12, the upper end of which extends into the channel 6, parallel and adjacent to the vertical arm 7^a. Rivets, or other suitable securing means 13 fasten the upper and lower end of the guide plate rigidly to the arms 7^a and 10 of the bracket, 15 and bolts 14, passing thru the overhanging flange 5 of the rail; the arm 7^a and the plate 12, serve to secure these members to each other and to the rail. It will be noted that the construction just described greatly reinforces the rail at this point, strengthening it against the stresses incident to the filling in of the paving material between the rails, and the weight of surfacing machines travelling thereover.

It will be noted that the guide plate 12 is bent inwardly intermediate its ends, as at 15, forming a slide-way 16 with the arms 7^a and 10 of the bracket, for a purpose about to be described.

The upper and lower sides 7 and 8 of the U bracket are provided with aligned apertures 17 thru which passes a stake 18 to be driven into the ground whereby the rail form may be securely held in proper position. The base flange 2 of the rail is cut away as at 19 to allow the stake to pass into the ground.

In order to lock the rail form to the stake and prevent any possibility of its displacement from properly aligned position, a wedge shaped locking element or cam is guided in the slideway 16 and engages the stake between such slideway and the vertical side 20 of the U bracket. This wedge includes two angle plates 21 and 22 of metal or other suitable material superimposed one upon the other and having two of their flanges, extending in opposite directions and in the same plane, as at 23 and 24, forming a guide or flange slidable in the slideway 16. The outer edge of this element is tapered as at 25 thereby forming a wedge which engages the inner face of the stake 18. One end 26 of the wedge, is provided with inturned ears 27 for engagement with the guide plate 12 to prevent the wedge from slipping out of its slideway when the wider part of said wedge is not in engagement with the stake.

It is preferable not to rely entirely on the surface provided by the adjacent edges of the wedge formed by the plates 21 and 22, for a positive lock for the stake 18, and for this reason there is secured to the top and bottom of these plates, as by rivets 28, additional plates 29 and 30 which are preferably

of steel and case hardened. The outer edges of these plates protrude slightly beyond the edges of the plates 21 and 22 as at 31 and 32, as shown in Figure 2, and are therefore first to engage the stake when the wedge is driven into locking position. If, as in most cases, the stake is of comparatively soft metal, the hardened edges 31 and 32 will cut or "bite" into the stake on either side of the edges of the plates 21 and 22 thus more than doubling the effectiveness of the locking element. If however the stake be of such material as to resist this "biting" action, the edges 31 and 32, because of their separation, form a very effective grip on the inner surface of the stake and prevent any possibility of a loose connection or of slipping.

The plates 29 and 30 possess the additional advantages of greatly reinforcing the wedge structure, and thereby the entire locking device, and of presenting a wider gripping surface along the stake engaging face of the wedge.

As the operation of the device described is obvious from the foregoing, no detailed explanation thereof is necessary. Of course it will be understood that the embodiment herein shown and described is the preferred form only, and that it is susceptible to various changes in details of construction and operation without departing from the scope of my invention. I do not limit myself therefore, other than by the appended claims.

I claim:

1. A road form comprising a rail, a stake receiving member secured thereto, and a stake securing device including a wedge shaped member having separated stake engaging surfaces.

2. A road form comprising a rail, a stake receiving member secured thereto, and a stake securing device including a wedge shaped member having a plurality of stake engaging surfaces.

3. A road form comprising a rail having flanges, a stake receiving member secured thereto, a stake in said member and a stake securing device including a wedge shaped member provided with means for biting into said stake at separated points.

4. A road form comprising a rail, a stake receiving member secured thereto, a stake in said member, a securing device including a wedge provided with means for biting into said stake at separated points, and a stake engaging surfaces on said wedge between said means.

5. A road form comprising a rail, a stake receiving member secured thereto, a stake in said member, a wedge movable in said member and provided with a plurality of stake engaging surfaces located in different planes.

6. A stake locking element for road forms

comprising a wedge provided with a guiding flange and a plurality of stake engaging surfaces.

7. A stake locking element for road forms comprising a wedge provided with a guiding flange and a stake engaging surface, and reinforcing means for said wedge.

8. A stake locking element for road forms comprising a wedge provided with a guiding flange and a stake engaging surface, re-

inforcing plates on said wedge, said plates also providing stake engaging surfaces.

9. A stake locking element for road forms comprising a wedge provided with a guiding flange and a stake engaging surface, re-inforcing plates on said wedge, said plates also providing stake engaging surfaces lying in a different plane than said first surface.

MARK S. HOTCHKISS.
